William W. Stevens, of Portland, Maine,
Assignor to
Nathaniel P. Richardson, & Co., of same place,
Letters Patent No. 1557, dated March 25, 1862.

The schedule referred to in these Letters Patent and making part of the same,

To all whom it may concern:

Be it known that I, William W. Stevens, of the City of Portland, County of Cumberland, and State of Maine, have invented a new and original design for a Cooking Stove which I term "The Superior," and I do hereby declare that the following is a full and exact description of the same, reference being had to the accompanying drawings, and to the letters of reference theron.

Of the said drawings -

In said drawings E. represent the doors of the oven. G. represents the side door or end door of the fire box. P.P. represents the front doors. and S.S. represents the legs of the stove.

I claim the configurations and ornaments above described and shown in the drawings as a design for a cooking stove.

In testimony whereof I have hereunto set my hand and seal this the nineteenth day of February A. D. 1862.

Witnesses.
